UNITED STATES PATENT OFFICE.

BESSIE PRIGMORE, OF PORTLAND, OREGON, ASSIGNOR TO JOHN E. KENNEY, OF PORTLAND, OREGON.

PORTABLE WASHING MACHINE.

Application filed February 19, 1923. Serial No. 619,899.

To all whom it may concern:

Be it known that I, BESSIE PRIGMORE, a citizen of the United States, and a resident of Portland, county of Multnomah, and State of Oregon, have invented a new and useful Improvement in Portable Washing Machines, of which the following is a specification.

My invention relates to washing machines and specifically to washing machines which have no tub connected therewith, and to attachments which are adapted to be mounted on a tub.

The object of my invention is to provide a portable washing machine which is compact and which is adapted to be readily attached to and detached from a standard stationary wash tray and is designed to work efficiently therein.

A further and more specific object is to provide a washing machine or attachment in which the dolly not only oscillates but also has devices connected therewith which perform a suction action and thus agitate the contents of the tub.

I attain these objects in a washing machine by means of the combination of a portable base having means for fastening the same to a wash tub or the like, the base adapted to constitute a cover for said tub and provided with a removable section which permits access to the tub without unseating the base therefrom, a prime mover mounted on said base, an oscillatable arm operatively connected with said prime mover, a hollow shaft journaled in said base for oscillation about a vertical axis, connections between said oscillatable arm and said shaft, a head carried by the lower end of said hollow shaft, a hollow perforated cylinder pendent from said head, a plunger reciprocable in said cylinder, a rod reciprocable in said hollow shaft, means for utilizing the oscillation of the latter to reciprocate said rod, an operative connection between the latter and said plunger.

These and other objects are illustrated in the accompanying drawings, in which:

Fig. 1 is a plan view of my device mounted on a portable base with a portion of the base broken away to show details of construction;

Fig. 2 is a section taken on the line 2—2

of Fig. 1 and shows the dolly head and the plunger operating mechanism in section; 55

Fig. 3 is a section taken on the line 3—3 of Fig. 1 with the dolly head shown substantially in full but with parts broken away to show details of construction.

My device is mounted on a portable base 60 1 which is made in a plurality of pieces.

Portions 1^a and 1^b are clamped to the tub 2 on one side by screw clamps 3 and portions 1^c and 1^d are hingedly attached thereto. The washing mechanism is mounted on 65 the piece 1^c which is held to the other side of the tub by releasable clamps 4. Portion 1^c covers the major portion of the top of the tub and the portion 1^d which is hinged to the section 1^b covers substantially 70 the rest. There is no mechanism mounted on the section 1^d and thus it can be readily raised upward and thus provides an easy access to the tub without unseating the mechanism. A prime mover as the motor 75 5 is mounted on the base 1^c and is connected to a rotatable worm 6 by a shaft 7 which has a flexible coupling 8 between the worm and the motor. The worm 6 80 meshes with the worm gear 9 which is mounted on the shaft 10 which is journaled vertically and thus normal to the horizontal shaft 7 on which the worm is mounted. This shaft is journaled in a casing 11 and its removable cap 12. The shaft 10 has 85 a horizontal arm 13 at its lower extremity which has a vertical crank pin 14. A horizontal lever 15 pivotally mounted on a pivot 16 is oscillated by this pin 14 extending thru the elongated hole 17. The end 18 90 of this lever 15 opposite the elongated hole 14 is arcuate and has teeth 19 and thus constitutes a segment of a gear. The teeth 19 mesh with the segment 20 mounted on the hollow dolly shaft 21. The dolly head 95 22 is connected to the lower end of the hollow dolly shaft 21 by means of the pin 23. The connection is made thru vertical slots 24 thus the dolly head is longitudinally movable on the shaft 21. The dolly shaft 100 is threaded as at 25 and the segment 20 is fastened to the dolly by means of this thread on one side of the base board 1^c and a locking nut 26 is fastened to the other side and is adapted to take up play 105 and form a wearing surface for the dolly

on the base board. The casing 11 has an elongated arm 27 which extends out and forms a wearing surface against which the lock nut 26 and the segment 20 wear so that the wear will not be on the base board 1^c. The hollow dolly shaft 21 has a rod 28 mounted in its bore. This rod is held against rotation on the dolly shaft by the bracket 29 which fits closely about the square end 28^a of this rod but permits it to move longitudinally in the bore. The pin 30 is fastened to the rod 28 and extends thru the spiral slot 31 in the hollow dolly shaft 21. Thus as the dolly shaft 21 rotates it moves the rod 28 longitudinally in its bore because the shaft is held against rotation by the bracket 29 and is moved longitudinally due to the action of the spiral slot 31 forcing the pin upwardly or downwardly.

The lower end of this rod 28 is pivotally fastened to a plurality of levers 32. These levers are pivotally mounted between the supports 33 and their free ends are connected to a plunger rod 34. Plungers 35 move longitudinally in the hollow dolly pegs 36 which are thus substantially cylinders. Thus as the levers 32 are moved the plungers 35 are moved longitudinally in these dolly pegs 36. These pegs are perforated as at 37 and thus it can be seen that if the dolly head was submerged in water the action of these plungers would be to draw water into these pegs or cylinders and force it out again consecutively during each stroke.

The operation of my device is as follows: The device is portable and easily transferred from one washing tray or tub to another and the clamps 3 and 4 fasten the board tightly to the tub. The motor 5 is then started and it rotates the shaft 7 and thus the worm 6. This worm being in contact with the worm gear rotates that on its vertical shaft 10. The shaft rotates the arm 13 and the crank pin 14 being seated in the elongated slot 17 moves the lever 15 about its pivot 16. This transmits the motion from rotary motion to horizontal oscillatory motion because the elongated slot 17 is slightly longer than twice the lever arm of the arm 13 and crank pin 14. Thus as the lever 13 is rotated it oscillates the lever 15 on its pivot 16. The opposite end of the lever 15 therefore rocks the gear segment 20 and therefore the hollow dolly shaft 21 and thus the dolly head 22. As heretofore described the rocking of the dolly shaft 21 moves the rod 28 longitudinally in the bore of the hollow dolly shaft 21 and thus causes the plunger 35 to move longitudinally in the bore of the hollow pegs 36. The dolly head therefore moves the clothes thru water in the wash tray and the plungers alternately force and suck water thru the clothes.

A wringer 38 is mounted on the base 1^c and driven by the shaft 39 which is connected to the vertical shaft 10 by means of a pair of double pinions, 40. A clutch 41 is provided in the shaft 39 so that the power can be connected or disconnected from the wringer. A similar clutch 42 is provided in the shaft 10 so that power can be connected or disconnected to or from the dolly shaft. The motor 5 can thus be operated so as to run the wringer separately or the dolly head separately or run them both simultaneously. An arm 43 fastened to the casing 11 acts as a bearing for the shaft 39 and a universal joint 44 connects the shaft 39 to the wringer 38 so that the wringer can be operated in any convenient position.

I claim:

1. In a washing machine the combination of a portable base having means for fastening the same to a wash tub or the like, a prime mover mounted on said base, an oscillatable arm operatively connected with said prime mover, a hollow shaft journaled in said base for oscillation about a vertical axis, connections between said oscillatable arm and said shaft, a head carried by the lower end of said shaft, a hollow perforated cylinder pendent from said head, a plunger reciprocable in said cylinder, a rod reciprocable in said hollow shaft, means for utilizing the oscillation of the latter to reciprocate said rod, and an operating connection between the latter and said plunger.

2. In a washing machine, the combination of a base, a prime-mover mounted on said base, an oscillatable arm operatively connected to said prime-mover, a hollow shaft journaled in said base for oscillation about a vertical axis, connections between said oscillatable arm and said shaft, a head carried by the lower end of said shaft, washing devices carried by said head, means for utilizing the oscillation of the hollow shaft to operate said washing devices.

3. In a washing machine, the combination of a base, a prime-mover mounted on said base, an oscillatable arm operatively connected to said prime-mover, a hollow shaft journaled in said base for oscillation about a vertical axis, connections between said oscillatable arm and said shaft, a head carried by the lower end of said shaft, a plurality of hollow perforated cylinders pendent from said head, a plunger reciprocal in each of said cylinders, a rod reciprocal in said hollow shaft, means for utilizing the oscillation of the latter to reciprocate said rod, and an operating connection between the latter and said plungers.

4. In a washing machine, the combination of a base, a prime-mover mounted on said base, an oscillatable arm operatively connected to said prime-mover, a hollow shaft journaled in said base for oscillation

about a vertical axis, connections between a rod reciprocal in said hollow shaft, means said oscillatable arm and said shaft, a head for utilizing the oscillation of the latter to carried by the lower end of said shaft, a reciprocate said rod, and an operating con- 10 plurality of hollow perforated cylinders nection between the latter and said plungers. 5 pendent from said head and arranged to diverge from a common vertical axis, a plunger reciprocal in each of said cylinders,

BESSIE PRIGMORE.
